UNITED STATES PATENT OFFICE.

FRANK E. BEAM, OF TOLEDO, OHIO, ASSIGNOR, BY DIRECT AND MESNE ASSIGNMENTS, TO THE AUTOMAT MOLDING AND FOLDING COMPANY, OF TOLEDO, OHIO, A CORPORATION OF OHIO.

CARTON.

Application filed October 7, 1920. Serial No. 415,306.

To all whom it may concern:

Be it known that I, FRANK E. BEAM, a citizen of the United States, and a resident of Toledo, in the county of Lucas and State of Ohio, have made an Invention Appertaining to Cartons; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to cartons of the type commonly used as containers for butter, ice cream bricks, and other commodities, and usually comprising a single piece of stiff paper folded in rectangular form.

In the folding and closing of the ends of these cartons, particularly when done by machine, considerable difficulty is experienced in inserting the tongue of one of the outer end flaps into holding position in the respective end edge portion of the carton without tearing or otherwise injuring the tongue or the parts with which it has contact during the inserting action.

The object of my invention is to overcome the objections above noted by so fashioning the carton blank as to facilitate the entry of the tongue of an end flap into closed or holding position in the carton without tearing or injuring the same, and at the same time not weakening the carton.

The invention is fully described in the following specification, and a preferred embodiment thereof illustrated in the accompanying drawings, in which,—

Figure 1 is a perspective view of a carton embodying the invention with the ends partly open and with parts broken away. Fig. 2 is a similar view thereof with the inner end flaps of one end completely closed and the outer end flap in open position, and Fig. 3 is an enlarged perspective view of an end portion of the carton with the tongue of the outer end flap in the act of being inserted into the carton.

Carton blanks of the type described, as customarily formed, have four foldably connected panels, 1, 2, 3 and 4 adapted to form different sides of the carton when folded, with one of the end panels, 4 in the present

instance, provided with an end flap 5 adapted to lap the inner side of the other end panel 1.

The sides 1 and 3 of the carton at one end thereof are provided with flaps 6 and 7, respectively, adapted to project in lapping relation inwardly from the ends. The flap 5, which laps the inner side of the side 1, is also provided at such end with a flap 8, which is lapped by the flap 6 and also by the end portion of the flap 7. The flaps 7 and 8 have their top edges, or those adjacent to the side 4 of the carton, cut on an incline so that they extend downwardly from their inner ends to adapt them when in folded position to leave a space between their upper edges and the adjacent end of the side 4 into which space the end tongue 9 of the respective outer end flap 10 may be inserted. The end flap 10 projects from the end of the carton side 2, being co-extensive in width therewith, and when folded is intended to lap the outer sides of the flaps 6 and 7 with its tongue 9 inserted under the end edge of the side 4.

The flap 6 is provided on its top edge, or the edge thereof which is lapped by the tongue 9, with a tongue or upward projection 11, which is formed by cutting such edge of the flap away from a point substantially at its inner end to near the outer end thereof, thereby providing a space between the adjacent end edge of the side 4 and the inner end portion of the adjacent edge of the flap 6. It is necessary to provide the tongue 11, which, when the carton is folded, is substantially flush with the inner side of the tongue 9, so that it coacts therewith to retain the adjacent end of the side 1 in close hugging relation to the adjoining edge of the side 4 at such end. In other words, if the flap 6 were not provided with the tongue 11 for coaction with the tongue 9 when the carton is folded, there would be nothing to prevent the adjacent free edge portion of the side 1 from falling outward away from the flap 5 and the adjoining edge of the side 4.

The opening which is provided between the end of the side 4 and the flaps 6, 7 and 8 at both sides of the tongue 11 by reason of the cutting away of the material at the upper edge of the flap 6 at the inner side of the tongue and also the cutting of the adjacent edges of the flaps 7 and 8 as shown,

is found in practice to be very important as it enables an easy finding of such opening by the tongue 9 when being directed into the carton end either by hand or by a machine, thereby facilitating the folding action and preventing the tongue 9 from tearing and straddling the end edge of the side 4 or being otherwise injured or from injuring the parts with which it coacts by reason 10 of its not being able to accurately find the space into which it is to be inserted. The tongue 11 is sufficiently flexible by reason of the material from which it is made as to enable it to be bent inward by the inserting 15 force of the tongue 9, thereby permitting the tongue to freely slide over the same into its closed position.

The opposite ends of the carton is made in the usual or any suitable manner and 20 therefore need not be specifically described.

I wish it understood that my invention is not limited to any specific construction, arrangement or form of the parts, as it may be changed without departing from the spirit 25 of the claims.

Having thus described my invention, what I claim as new, and desire to secure by Letters Patent, is,—

30 1. A carton having an inner flap and an outer flap projecting from adjacent ends of adjoining sides and adapted to lap each other when in folded relation, the outer flap having a tongue at its outer end for insertion into the carton body over a side edge 35 of the inner flap, and said inner flap having a tongue at the side edge thereof which is lapped by the outer flap tongue and which coacts therewith to retain the carton sides in folded relation.

40 2. A carton formed of a blank having four side panels with the side edges of the panels adjoining, an inner flap projecting inwardly from an end of one panel and having a tongue at a side edge thereof, which tongue 45 is spaced from the panel from which it projects and from the opposite panel, an outer flap projecting from the end of a panel disposed at the side of the inner flap opposed to its tongue and adapted to lap the inner 50 flap to cooperate therewith to close the end of the carton, the free end of the outer flap having a tongue for insertion into the carton

between the tongued edge of the inner flap and the respective end of the adjacent side panel, the tongues of the two flaps cooperating to prevent an unfolding movement of the panel from which the inner flap projects.

3. A carton formed of a single piece blank having a plurality of side panels adjoining at their sides, inner flaps projecting from adjacent ends of opposing side panels in lapping relation and an outer end flap projecting in adjacent relation to the inner flaps from an end of a side panel disposed between the side panels from which the inner flaps project, said outer flap being adapted to lap the inner panels and having a tongue at its free end for insertion into the carton body between the adjacent side edges of the inner flaps and the side panel which is opposed to that from which the outer tongue projects, one of the inner flaps having the edge thereof which is overlapped by the tongue of the outer flap cut away and the other inner flap having its corresponding edge provided with a tongue which coacts with the outer flap tongue intermediate its side edges to retain the carton sides in folded relation.

4. A carton formed of a single piece blank having a plurality of side panels adjoining at their sides, two of which lap each other, one of the lapping side panels and the opposing side panel having inner flaps projecting from their adjacent ends for lapping each other and being cut away at one side edge, a third inner flap projecting from an end of the other lapping side panel and disposed in lapping relation to the other flaps, and an outer flap projecting from an end of a different side panel and adapted to lap the inner flanges and having a tongue at its outer end for insertion into the carton body over the cut away side edges of the first two inner flaps and a side edge of the other inner flap, said side edge of the other inner flap having a yielding tongue which is spaced from the panels from which the inner flanges project and coacts with the outer flap tongue to retain the carton sides in folded relation.

In testimony whereof, I have hereunto signed my name to this specification.

FRANK E. BEAM.
